METAL TRELLIS

Wade L. Linamen, Warren, and Stanley L. Woofter, Nutwood, Ohio

Application September 13, 1946, Serial No. 696,696

3 Claims. (Cl. 47—47)

1

The invention relates to a new and improved vine trellis constructed entirely from light metal, one object of the invention being to provide a simple and inexpensive construction in which the two outermost of a plurality of upwardly diverging trellis bars coact with two parallel plates between which the lower ends of said bars are secured, in forming a stake to be driven into the ground to anchor the trellis.

Another object is to provide a novel construction in which at least two of the upwardly diverging bars have longitudinal channels facing each other to accommodate a spreader bar, one or more vine supporting rods and a bag of threaded fasteners, when said spreader bar and said rod or rods are detached from the upwardly diverging bars and the latter are sprung inwardly into compact relation with each other for storage or shipment.

A further object is to provide an extremely simple and inexpensive, yet a strong and durable construction.

Figure 1 is a side elevation of the trellis in readiness for use.

Fig. 2 is a side elevation showing the trellis wired in compact condition for storage or shipment.

Fig. 3 is a fragmentary sectional view through the upper portions of a number of the upwardly diverging bars, and the spreader secured to the upper extremities thereof, and illustrating one of the vine-supporting rods engaged with said upwardly diverging bars.

Fig. 4 is a vertical sectional view through the stake-forming portion of the trellis and the lower ends of the upwardly diverging bars.

Fig. 5 is an edge view of the stake-forming portion of the trellis.

Fig. 6 is a horizontal section on line 6—6 of Fig. 4.

Fig. 7 is a horizontal section on line 7—7 of Fig. 2.

A construction has been shown which has proven advantageous from standpoints of manufacture, storage, shipment and sale, and while that construction is preferred, minor variations may be made within the scope of the invention as claimed.

Two parallel, vertically elongated, laterally spaced metal plates 8 are provided, each of said plates having two downwardly converging edges 9. The upper end of each plate is bent laterally outward at 10 for a purpose to appear.

A plurality of upwardly diverging bars are secured at their lower ends between the plates 8

and are welded at 11 to the upper ends of said plates. There are preferably six of these bars, the two outermost being denoted at 12, the two innermost at 13, and the others at 14. All of these bars are preferably of channel-shape in transverse section and the channels of all bars at each side of a central line, open inwardly toward said line. The lower end portions 16 of the two bars 12 are substantially flush with the downwardly converging edges 9 of the plates 8 and are welded thereto as shown at 17 (Fig. 5), said portions 16 thus coacting with the plates 8 in forming a rigid stake to be driven into the ground to anchor the trellis. When performing the driving operation, the laterally bent plate ends 10 constitute driving shoulders to be struck with a hammer or other tool.

At the upper ends of the bars 12, 13 and 14, the side flanges of these bars are cut off and the flange-connecting portions of said bars are bent laterally inward to provide lugs 18 to which a spreader bar 19 is secured by bolts or screws 20. Between their ends, the bars 12, 13 and 14 are formed with openings 21 to receive vine-supporting rods 22.

At the factory, the bars 12, 13 and 14 are sprung inwardly into compact relation with each other (see Fig. 2) and are secured by a wire 23 which is passed through the upper set of the openings 21 and has its ends twisted together at 24. The inwardly facing channels of the bars 13 then effectively accommodate the spreader bar 19, a package 25 containing the rods 22, and a bag 26 containing the fasteners 20. The bag is preferably of the draw-string type with its draw-string suspended from the wire 23, and this wire is passed through the package 25 between the rods 22, to suspend said package. If desired, the wire may be drawn much tighter than shown in Figs. 2 and 7, drawing the bars 12, 13 and 14 and the parts engaged with them, into much more compact relation. The spreader bar 19 will readily nest with one of the bars 13 as seen more particularly in Fig. 7, and the channel of the other bar 13 may contain the bag 26 or the package 25. The entire assemblage will thus occupy relatively small space for storage at the factory, for shipment, for storage at the retailer's, and for delivery to his customers. The structure may be readily assembled for use and easily driven into the ground, and if it be desired to take the trellis indoors during the winter, it may again be easily restored to the compact condition of Figs. 2 and 7.

From the foregoing, taken in connection with

the accompanying drawings, it will be seen that novel and advantageous provision has been made for carrying out the objects of the invention, and while preferences have been disclosed, attention is again invited to the possibility of making variations within the scope of the invention as claimed.

We claim:

1. A metal trellis comprising two vertically elongated parallel plates each having two downwardly converging edges, a plurality of upwardly diverging bars secured at their lower ends between said plates, the two outermost of said bars being substantially flush with said downwardly converging edges of said plates and extending to the lower extremities thereof, whereby the lower portions of said outermost bars coact with said plates in forming a pointed stake to be driven into the ground, and a spreader connected with said upwardly diverging bars.

2. A structure as specified in claim 1; the upper ends of said plates being bent laterally outward to provide driving shoulders.

3. A metal trellis including a plurality of up-

wardly diverging bars connected at their lower ends and springable inwardly into compact relation when desired, and transverse members removably connected with said upwardly diverging bars, at least two of said upwardly diverging bars being of channel shape in transverse section and having their channels disposed toward each other; whereby said channels may accommodate said transverse members when the latter are detached and said upwardly diverging bars are tied in inwardly sprung compact relation.
